UNITED STATES PATENT OFFICE.

BOYD A. SIGLER, OF SIOUX FALLS, SOUTH DAKOTA.

AERIAL BOMB.

1,312,005.

Specification of Letters Patent. Patented Aug. 5, 1919.

Application filed August 5, 1918. Serial No. 248,360.

To all whom it may concern:

Be it known that I, BOYD A. SIGLER, a citizen of the United States, residing at Sioux Falls, in the county of Minnehaha 5 and State of South Dakota, have invented certain new and useful Improvements in Aerial Bombs, of which the following is a specification.

My invention relates to improvements in 10 aerial bombs.

An important object of the invention is to provide a bomb of the above mentioned character having means whereby a plurality of relatively small projectiles are first 15 thrown from the body of the bomb, upon the same striking the ground or target, and subsequent to which the body of the bomb is exploded, and thrown in divers directions.

A further object of the invention is to 20 provide a bomb of the above mentioned character, having the projectile receiving openings arranged in the wall thereof, in such a way that the wall is rendered breakable into sections, which are projected in 25 divers directions.

A further object of the invention is to provide a bomb of the above mentioned character which is automatic in operation.

Other objects and advantages of the invention will be apparent during the course 30 of the following description.

In the accompanying drawings forming a part of this specification and in which like numerals are employed to designate like 35 parts throughout the same,

Figure 1 is a central vertical longitudinal sectional view through a bomb embodying my invention,

Fig. 2 is a horizontal transverse sectional 40 view taken on line 2—2 of Fig. 1,

Fig. 3 is a similar view taken on line 3—3 of Fig. 1,

Fig. 4 is an enlarged sectional view 45 through the wall of the bomb, showing the projectile receiving openings,

Fig. 5 is a similar view, showing a different form of projectile, and,

Fig. 6 is a fragmentary side elevation of 50 the wall of the bomb, showing the manner in which the projectile receiving openings are arranged.

In the drawings, wherein for the purpose of illustration is shown a preferred embodiment of my invention, the numeral 55 10 designates the body portion or shell of the bomb which is preferably formed of

iron, steel or the like. This shell is preferably circular in cross-section, tapering toward its forward and rear ends, to insure accuracy in flight. The bomb is provided 60 near its rear end with vanes 11, as shown.

At its forward end, the shell 10 has a reduced screw-threaded portion 12, fitting within a screw-threaded recess formed in a tapered nose 13, which forms in effect a continuation of the shell 10.

The shell 10 is provided with radially extending openings 14, which pass through the inner and outer sides of the wall thereof. The openings 14 are arranged in longitudinal and horizontal circumferential groups, providing relatively large portions or squares 14' which are readily breakable from each other, by virtue of these openings, as will be more fully explained. These 70 75 openings are adapted for the reception of relatively small projectiles or bullets 15. Instead of employing a single bullet 15, I may employ a wrapper 16, filled with shot or small projectiles 17, as shown. 80

The shell 15 is filled with a propelling charge 18, and this charge, upon exploding, forces the projectiles 15 through and from the openings 14.

The nose 13 is provided with an interior 85 recess, filled by a plug 19. This plug has a chamber 20, and passages 21, formed therein. The passages 21 lead to the projecting charge 18, as shown.

Arranged centrally and longitudinally 90 within the shell 10 is an exploding member 22, filled with an exploding charge 23. The member 22 is inserted within a thin metallic casing 24, held in place by stationary lugs 25, secured to the shell 10. The member 22 95 is capable of moving forwardly longitudinally within the casing 25, and this movement is normally opposed and prevented by a compressible coil spring 26. A combined cap and fuse 27 is secured to the plug 19 and 100 leads to the chamber 20, while a longer combined cap and fuse 28 is secured to the lower end of the member 22 and leads to the interior thereof.

When the projectile is dropped from a 105 flying machine or the like, the same descends by gravity and upon contacting with the ground or target, the member 22 moves forwardly with relation to the shell 10. This movement brings the combined cap and fuse 110 28 into contact with the combined cap and fuse 26, whereby they are both ignited. The

- cap or fuse 26 being shorter, the charge within the chamber 19 is first ignited, which at once ignites the charge 18. This propelling charge, upon explosion thereof, forces the 5 projectiles 15 through the openings 14. Subsequent to this operation, the exploding charge 23 is ignited, and the entire bomb including the shell 25, is blown to pieces. The 10 openings 14 by being arranged in the precise manner, as illustrated in Fig. 6, form relatively large portions or squares 14', which are readily breakable from each other, and these portions or squares are projected in divers directions.
- 15 It is to be understood that the form of my invention herewith shown and described is to be taken as a preferred example of the same, and that various changes in the shape, size, and arrangement of parts may be 20 sorted to without departing from the spirit of my invention or the scope of the subjoined claims.

Having thus described my invention, I claim:

- 25 1. An aerial bomb of the character described, comprising an outer shell having a plurality of transverse projectile openings, projectiles for insertion in the openings, a cap secured to the forward end of the outer shell and having an interior recess, a plug arranged within the interior recess and having a main inner chamber and ports extending outwardly therefrom and leading into the interior of the outer shell, an inner tube 30 extending longitudinally of the outer shell, a firing charge arranged within the space between the outer shell and inner tube and

leading to the ports, a casing mounted to reciprocate within the inner tube, an exploding charge arranged within the casing, a combined cap and fuse anchored within the inner portion of the plugs and having one end projecting into the tube and the other end extending into the main chamber of the plug, a combined cap and fuse anchored to the forward end of the reciprocating casing and having its rear end extending through the same and its forward end projecting forwardly beyond the casing, said second named combined cap and fuse being substantially 50 longer than the first named combined cap and fuse and adapted to contact with the first named combined cap and fuse, and yielding means to oppose the forward movement of the casing.

55 2. A device of the character described, comprising an outer casing having a plurality of transverse openings, projectiles for insertion within the openings, an inner tube extending longitudinally within the outer casing, an exploding charge arranged within the outer casing exteriorly of the inner tube, an inner casing arranged within the longitudinal tube and adapted to move forwardly therein, means to oppose the forward movement of the inner casing, an exploding charge within the inner casing, and means operated by the forward movement of the inner casing to fire the first named exploding charge and subsequently 60 fire the second named exploding charge.

65 In testimony whereof I affix my signature.

70 BOYD A. SIGLER.
